UNITED STATES PATENT OFFICE

ALMER H. BRODBECK, OF ST. LOUIS, MISSOURI, ASSIGNOR TO AMERICAN STOVE COMPANY, OF ST. LOUIS, MISSOURI, A CORPORATION OF NEW JERSEY

DESIGN FOR A RANGE

Application filed April 8, 1931. Serial No. 39,401. Term of patent 14 years.

To all whom it may concern:

Be it known that I, ALMER H. BRODBECK, a citizen of the United States, residing in the city of St. Louis and State of Missouri, have invented a new, original, and ornamental Design for Ranges, of which the following is a specification, reference being had therein to the accompanying drawings.

In the accompanying drawings:

Figure 1 is a perspective view of a range embodying my new design, said range having its movable parts in closed positions.

Fig. 2 is a perspective view of Figure 1 showing the movable parts of the range in open positions.

The dominant feature of the design comprises a structure as shown provided at its

right side with an elevated small compartment and below it a relatively large compartment and at the left side an upper large compartment which extends below the said small compartment and below this large compartment a small compartment, and the large compartment at the left having a cover which when open exposes substantially its left hand end and when closed it closes this left hand end thus producing the design shown.

I claim:

The ornamental design for a range as shown and described.

In testimony whereof, I hereunto affix my signature.

ALMER H. BRODBECK.
